DESIGN FOR A DRESS

Oscar Zaretzky, New York, N. Y.

Application October 23, 1937, Serial No. 72,379

Term of patent 3½ years

To all whom it may concern:

Be it known that I, Oscar Zaretzky, a citizen of the United States of America and resident of the county of Bronx, city and State of New York, have invented a new, original, and ornamental Design for a Dress, of which the following is a specification, reference being had to the accompanying drawing, forming a part thereof.

In the drawing:

Figure 1 is a front view of a dress embodying my design.

Figure 2 is a back view thereof.

The characteristic feature of my design resides in the combination on the back opening dress disclosed of the representation of a turned down collar stitched at the outer edges of the dress, the inner edges forming a V-shaped opening in the front, and continuing to form a close fitting collar in the rear, in association with the belt and necklace as shown.

I claim:

The ornamental design for a dress substantially as shown and described.

OSCAR ZARETZKY.
